UNITED STATES PATENT OFFICE.

DANIEL F. LEPLEY, OF CONNELLSVILLE, PENNSYLVANIA

BLAST-FAN.

No. 905,195.

Specification of Letters Patent.

Patented Dec. 1, 1908.

Application filed March 11, 1908. Serial No. 420,482.

To all whom it may concern:

Be it known that I, DANIEL F. LEPLEY, a citizen of the United States, residing at Connellsburg, in the county of Fayette and State 5 of Pennsylvania, have invented a new and useful Blast-Fan, of which the following is a specification.

This invention has reference to improvements in blast fans, being designed more 10 particularly for use where a large volume of air under sufficient pressure to drive the same for long distances is desired.

Experience has demonstrated that for best 15 results the blast fan should have the center of the fan wheel or rotor of open construction with the blades designed to direct air toward the periphery of the fan from whence the air is conducted to the point of utilization.

It is the object of the present invention to 20 so construct blast fans of the open center type as to avoid certain objectionable features which have been found to be present in blast fans as heretofore constructed.

By arranging the blades tangentially to a 25 circle less than the diameter of the central orifice or intake of the fan, the air entering through such intake is scooped up and directed toward the periphery of the fan and 30 there thrown off into a suitable chamber from whence the air is conducted away. The tangential blades are of course further apart at their outer ends than at their inner ends and air taken into the rotor at the intake 35 ends of the blades is by the rotative motion of the fan body caused to be packed or compressed against the active faces of the blades. This compression or compacting of the air as well as the increasingly 40 larger area of the space between each blade and the preceding blade causes a rarefaction of the air behind each blade, and the rarefaction will depend upon the distance between the outer ends of the blades as compared 45 with the inner ends thereof. When the distance between the outer ends of the blades exceeds a certain proportion with relation to the distance between the inner ends of the blades, then the rarefaction becomes 50 so great that the air passing outward over the active face of the blade will be caused to eddy or surge over the outer end of the blade into the space back of the blade. The effect of this is that there is produced a chattering or throbbing action when the fan is in

operation which is intensified as the diameter of the fan is increased until in large fans it may even become destructive to the fan structure.

In accordance with the present invention 60 the fan rotor is provided with a number of blades, which may be termed main fan blades, and this number depends upon the size of the rotor. When the diameter of the fan is such that the space between the 65 peripheral ends of the fan blades exceeds a certain approximate relation to the distance between the intake ends, then there is introduced between the blades other shorter 70 blades with their outer ends at the periphery of the rotor and terminating at a greater distance from the axis of the rotor than do the main blades. By this means the outgoing streams of air from the intake end of the fan instead of compacting against the active faces 75 of the main blades to such an extent as to cause the chattering or throbbing referred to are divided up before reaching the outer edge of the fan into a greater number of streams with the sizes of the spaces between the 80 outer ends of the fan blades so related to the distances between the inner ends of the fan blades that the rarefaction of the air streams adjacent to the inactive faces of the blades is so reduced as to obliterate the throbbing 85 or chattering and to also prevent any material retardation to the outflow of the air in its active direction. In the still larger types of fans the spaces between the outer ends of the main blades and of the intermediate 90 blades will again be too great and the throbbing or chattering will again be present. Under these conditions there is introduced between each intermediate blade and the next adjacent main blade an auxiliary blade 95 shorter than the intermediate blade. All the blades, however, terminate at the periphery of the rotor.

When the fans are in operation there is a clearance space between the sides of the 100 rotor member and the casing within which the fan is mounted, and because of the resistances offered to the outward movement of the air delivered by the fan, a comparatively large volume of air will find its way 105 through this clearance space because it constitutes a path of least resistance. Unless provision be made for the prevention of the effect of this returning stream of air it will retard the inflow of air at the intake of the 110

fan and thus very materially reduce the efficiency of the fan.

In accordance with the present invention the blowing out of the air through the clearance space and the consequent lowering of the efficiency of the fan is prevented by carrying the long or main blades for a distance into the space at the center of the wheel though not for a sufficient distance to interfere with the intake action of the fan. Under these circumstances any air which may find its way backward along the clearance space is met by the in-rushing stream of air and is carried again to the fan blades to be thrown outward toward the delivery end of the fan, and this occurs without retarding to any appreciable extent, the inflow of air at the central portion of the fan. Furthermore, the cheek plates of the fan rotor 20 terminate at their inner edges at a greater distance from the axis of the fan than the distance of the walls of the casing defining the intake opening, while the long or main blades of the fan rotor extend toward the 25 center or axis of the fan for a distance closer to said axis than is the defining edge of the intake opening in the casing. The intermediate blades terminate at the inner edge of the cheek plates, and for the best 30 results it is found that the inner edges of the cheek plates and the inner ends of the intermediate blades should terminate at a point as far outward from the defining wall of the casing orifice as the main blades project inward therefrom toward the axis of 35 the rotor. The clearance between the cheek plates and the adjacent walls of the casing thus terminates at a greater distance from the axis of the rotor than does the defining 40 wall of the intake opening in the casing. Consequently, any air which may find its way through these clearance spaces toward the intake opening will find its way into the active portion of the fan before the intake opening is reached and, therefore, instead of retarding the movement of the air into the intake opening it will participate 45 in the movement of the air toward the active portion of the fan.

50 The main fan blades as well as the intermediate and auxiliary blades are formed with their inner ends tangential to a circle of less diameter than the intake opening of the fan while their outer ends, all of which 55 terminate at the periphery of the fan, may be made approximately radial but preferably pitched slightly forward tangential to a small circle concentric with the axis of the rotor. This will give a slightly forward 60 throw to the outgoing streams of air and prevents any air from eddying or surging back of the active surfaces of the blades around the peripheral edges thereof.

65 The invention will be best understood, from a consideration of the following detail

description taken in connection with the accompanying drawings forming part of this specification, in which drawings,—

Figure 1 is a side elevation, with parts in section and parts broken away, of the rotary member of a blast fan made in accordance with the present invention. Fig. 2 is a similar view of a fan rotor of smaller size than that shown in Fig. 1. Fig. 3 is a section on the line A—B of Fig. 2, showing the fan 75 in position in the fan casing. Fig. 4 is a cross section of a portion of a fan, constructed in accordance with the present invention. Fig. 5 is a similar section of a form of fan heretofore used. 80

Referring to the drawings there is shown a shaft 1 which may be taken as a power shaft to which a suitable driving force is applied and by means of which the rotor of the fan is carried and driven. Fast on the 85 shaft 1 are a suitable number of radial arms 2, the number depending upon the size of the fan rotor and the strains to be resisted by the structure. In the drawings but four radial arms are shown, but it is to be understood that six or eight or more arms may be employed, as necessary. These arms 90 carry at their outer ends an annular cheek or flange 3, having its periphery 4 coincident with the outer edge of the fan rotor 95 and also having an edge 5, to which reference will hereinafter be made.

In the particular structure shown there are two annular cheeks 3 spaced apart and supported by arms 2 secured to suitable hubs 100 fast upon the shaft 1, and the hubs are spaced apart and are also connected together by a suitable drum 7 formed with two members secured together at their meeting faces. Between these meeting faces is secured a 105 web 8 which may be made up of segmental sections extending to the outer periphery of the rotor. The fan is, therefore, made up of a central web and two annular cheeks each spaced from a corresponding side of the 110 web while between the cheeks the rotor of the fan is provided with a suitable number of fan blades, as will hereinafter appear. Secured to the web 7 and the corresponding cheek plate on each side thereof is an annular series of equally spaced fan blades 9 being held in place by suitable angle irons 10, it being understood that in the particular instance shown the fan is built of metal, the web and cheek plates being of sheet metal of 115 suitable thickness and the fan blades also being of sheet metal of suitable thickness, while the parts are secured together by angle irons and the whole structure is suitably riveted. The fan blades 9, which may be 120 termed the long or main blades, have a portion 11 extending from the periphery of the fan rotor inward for a distance radially or substantially radially to the rotor body. Another portion 12 of the fan blades extends 125

tangentially at an angle of about 20° more or less to a line radial to the shaft 1, which line the portion 12 of the fan blade if continued would ultimately intersect at the 5 periphery of the fan body. In mentioning the angle as 20° , this is not to be taken as an absolute figure since a variation of a few degrees on either side would still produce good results, but experience has shown 10 that when the fan blade is at an angle of about 20° most excellent results are obtained. The tangential portion 12 of the fan blade extends into the open central portion of the fan body for a suitable distance. The outer 15 side of the fan blade is secured at its inner end to a ring 13, the inner ends of the several fan blades 8 being all secured to such a ring on each side of the diaphragm 8.

Let it be supposed that a fan having its 20 rotor provided with blades 9 as described and shown in Figs. 1 and 2, is being rotated counter clockwise, as viewed in said figures. Considering but one set of blades on one side of the diaphragm 8, which structure might be used in smaller types of fans, 25 it will be seen that the air within the rotor is scooped up and directed by the tangential members 12 of the fan blades toward the periphery of the fan rotor. This will at once 30 create a vacuum or partial vacuum or rarefaction at the inner open portion of the fan, and the surrounding atmosphere will rush in to restore the normal pressure thus reduced. The outwardly-moving columns of 35 air directed by the tangential portions 12 of the blades 9 ultimately reach the radial or approximately radial portions 11 of the blades and are thereby thrown more directly outward in a radial line than would occur 40 were the blades tangential throughout their length.

Considering only the blades 9 it will be seen that their outer ends, because of the tangential inclination of the blades are 45 spaced apart for a considerable distance which is much in excess of the spacing of the inner ends of the blades, and this peripheral spacing is also greater than though the blades were radial. The outwardly flowing streams of air scooped up by the blades are directed by the latter into portions of 50 the fan of constantly increasing cross sectional area. The forward rotation of the fan blades tends to pack or condense the air 55 against the active faces of the fan blades, thereby causing rarefaction of the air streams at the inactive face of each next preceding blade. If the fan rotor be comparatively small, then the relation of the 60 distance between the outer ends of two adjacent fan blades to the distance between the inner end of one of the fan blades and the next preceding fan blade, measured on a line perpendicular to the active face of the 65 said preceding fan blade will be such that

the outgoing air streams are of sufficient density, even adjacent to the inactive wall of the preceding blade, so that there is no tendency, to any material extent, of the air streams on leaving the blades to eddy or 70 surge back around the outer edge of the blade into the space back of the blade with relation to its direction of travel. When, however, the fan rotors are of greater diameter and there is a marked difference in the density of the 75 air streams in different parts of the space between the active face of a fan blade and the rear face of the next preceding blade so that there is formed an area of rarefaction immediately adjacent to the rear face 80 of the preceding blade, then there is a tendency of the air when passing beyond the peripheral edges of the blades to eddy or surge back into the area of rarefaction, and not only retard the outward movement of 85 the air under the action of the fan blades, but this surging or eddying of the air currents sets up throbings or chattering, which in the larger types of fans may even become destructive to the fan structure. Even 90 though such beatings or throbings should not be sufficiently intense to become destructive still they interfere with the smooth running of the fan rotor. To overcome this difficulty there is introduced midway between the blades 9, other blades 14 each having a tangential portion 15 and substantially radial portion 16. These intermediate blades extend from the periphery 4 of the cheek plates to the edge 5 but do not extend 95 into the open throat of the fan body. In this structure, which is shown in Fig. 2, the best results are obtained when the distance between the inner end of the tangential portions 15 and the next preceding blade 9 100 measured on a line perpendicular to the face of the tangential portion 12 of said preceding blade as indicated by the dotted line *b*, is approximately two-thirds of the distance between the inner end of the tangential portion 12 of the blades 9 and the next preceding blade 9 measured on a line perpendicular to the face of said preceding blade as indicated by the dotted line *a*. Also the distance from the inner edge of the 110 tangential portion 15 of the blade 14 and the face of the tangential portion 12 of the succeeding blade 9, measured on a line perpendicular to said face as indicated by the dotted line *c*, should likewise be less than the 115 distance between the inner edge of a blade 9 and the preceding blade 9 measured on the line *a* as before. Also the sum of the distances between the inner edge of any intermediate blade 14, and both the preceding 120 and succeeding blades 9 measured on the perpendiculars *b* and *c* as before should approximate one and one-half times the distance between the outer or peripheral end of 125 an intermediate blade 14 and the correspond- 130

ing end of the adjacent blade 9, it being understood that all the blades reach to and terminate at the periphery of the fan rotor, which is coincident with the periphery of the cheek plates.

Considering a fan rotor of still greater diameter, for instance, as indicated in Fig. 1, then the distance between the outer ends of the blades 9 and 14 ultimately becomes so great that the rarefied areas are again produced and throbbing or beating is set up. Under these circumstances, it becomes necessary to introduce between each intermediate blade and the next succeeding main blade, other auxiliary blades shorter than the intermediate blades. These blades are indicated at 17 and may be made of a substantial radial portion 18 and a tangential portion 19. The blades 17 reach from the periphery of the rotor inward to a point where their inner ends are related to the adjacent blades 9 and 14 in the same manner as described with relation to the inner ends of the blades 14 and the adjacent blades 9. That is, the sum of the distances between the inner end of a blade 17 and the adjacent walls of the blades 9 and 14 should not exceed about one and one-half times the distance between the outer end of a blade 17 and the adjacent outer end of a blade 9. If the fan rotor be still further enlarged then additional auxiliary blades are added to maintain the approximate equal spacing, as set forth. As an example, the proportions of a fan constructed as described, wherein both theory and practice have demonstrated the correctness of the proportions, it may be stated that the number of long or main blades should be such that the combined areas of all the spaces included between the inner ends of the tangential sections 12 and the next adjacent longer or main blades measured in a plane perpendicular to the face of the preceding tangential portion 12 should equal the area of the corresponding intake opening in the casing. It is found that the total number of blades may approximate one and one-half times the diameter of the rotor in feet. The radial length of the blades should be about one-eleventh of the diameter of the rotor. The tangential length of the main blades should be about one-fourth of the diameter of the rotor, and these tangential portions should be tangential to a circle, the diameter of which is about one-third of that of the rotor. The diameter of the circle including the inner ends of the tangential members of the main or long blades should be about two-fifths of that of the rotor, while the diameter of the circle described by the inner ends of the intermediate blades 14 should be about that of the rotor of the fan divided by 1.7.

As viewed in Fig. 3, the outer casing of the fan is shown at 20 and this is also shown

at 21 in Fig. 4, leaving a clearance space 22 between the cheek plates 3 and the adjacent walls of the casing 21.

It is customary in blast fans as heretofore constructed to carry the blades radially outward from the shaft, as indicated in Fig. 5, where the power shaft is shown at 23 and the blades at 24. In this case the outer casing 25 extends down toward the intake throat of the fan while the blades carry 75 angle irons 26 designed to support the blades, but the clearance space is thereby increased.

With a structure such as described in Fig. 5, which though in a measure diagrammatic, still represents the conditions present in 80 practical forms of blast fans, back pressure against which the fan works is sufficient to drive a comparatively large quantity of air out through the clearance space and direct it away from the fan. This is due to the fact 85 that the clearance space presents but little resistance to the escape of the air as compared with the back pressure on the discharge side of the fan. Furthermore, the escaping and wasted stream of air also tends 90 to retard the inflow of air at the intake throat of the fan and so the general efficiency of the fan is much reduced.

I have found from both theoretical considerations and from practical experience 95 that the main fan blades should not extend beyond a certain approximate distance into the intake throat, and further that the cheek plates and the intermediate fan blades should terminate at a greater radial distance 100 from the axis of the rotor than the defining wall or walls of the intake. The best results are obtained when the intake walls are about midway between the inner ends of the long blades and the inner ends of the intermediate blades, which inner ends of the intermediate blades are coincident with the inner edge of the cheek plates. Now, should air be forced backward through the clearance space between the cheek plates and the casing 105 it is met by the inrushing stream of air entering the throat of the fan and is directed into contact with the main fan blades to be again thrown out to the discharge end of the fan. Thus, no air is lost and there is no retarding action to any noticeable extent to the inrushing stream of air at the inlet of the fan.

What is claimed is:

1. In a centrifugal blast fan, a fan casing 120 with a central intake opening, a rotor therein having cheek plates with a central opening larger than the intake opening, and alternate main and intermediate blades extending inward from the periphery of the 125 rotor approximately radial to the axis of said rotor for a portion of their length and then tangentially for the greater portion of their length, the main blades terminating inside the periphery of the intake opening 130

- nearer to the said periphery than to the axis of the rotor and the intermediate blades terminating at the inner periphery of the opening in the cheek blades.
5. 2. A blast fan rotor having main, intermediate and auxiliary blades all extending inwardly from the periphery of the rotor approximately radial to the axis thereof for the same distance and then tangentially for 10 the remainder of their length, the main, intermediate and auxiliary blades terminating at respectively greater distances from the axis of the rotor.
3. A blast fan rotor having main, intermediate and auxiliary blades all extending inwardly from the periphery of the rotor and all having substantially radial outer portions of the same length and the inner portions tangential, the said tangential portions 20 of the different sets of blades being progressively shorter in the order named with the tangential portions of the auxiliary blades shorter than the radial portions of the same blades.
25. 4. A blast fan rotor, having cheek plates and main and intermediate blades extending inwardly from the periphery and terminating respectively inside and outside of the limits of the fan orifice, the intermediate 30 blades terminating at the inner edge of the cheek plates and the main fan blades extending beyond the same into the fan orifice.
5. A blast fan having main and intermediate blades extending inwardly from the 35 periphery and terminating at approximately equal distances inside and outside of the boundary of the fan orifice.
6. A blast fan having blades extending inwardly from the periphery and terminating 40 at a distance from the axis of rotation, the sum of the areas of the spaces included between the inner end of each blade and the surface of the next adjacent blade in a plane perpendicular to the active face of the latter 45 being approximately equal to the area of the fan orifice.
7. A blast fan having main and intermediate blades extending inwardly from the periphery and terminating at different distances 50 from the axis of rotation, the distance between the inner edge of each main blade and the surface of the preceding main blade on a line perpendicular to the latter being greater than the distance between the 55 inner edge of each intermediate blade and the surface of the preceding main blade on a line perpendicular with the latter.
8. A blast fan having main and intermediate blades extending inwardly from the 60 periphery and terminating at different distances from the axis of rotation, the distance between the inner edge of each main blade and the surface of the preceding main blade on a line perpendicular to the latter 65 being greater than the distance between the inner edge of each intermediate blade and the surface of the succeeding main blade on a line perpendicular to the latter.
9. A blast fan having main and intermediate blades extending inwardly from the 70 periphery and terminating at different distances from the axis of rotation, the distance between the inner edge of each main blade and the surface of the preceding main blade on a line perpendicular to the latter 75 being greater than the distance between the inner edge of each intermediate blade and the surface of either the preceding or succeeding main blade on a line perpendicular to the latter.
10. A blast fan having a central intake orifice with blades extending thereinto and a free clearance space opening into the active portion of the fan at a greater distance from the axis of rotation than the outer limits of 80 the intake orifice.
11. A blast fan having an open and substantially unobstructed intake with fan blades having substantially radial outer ends extending to the outer edge of the fan rotor 90 and having the inner ends entering the intake tangentially at an angle of about 20° to the radius of the fan rotor which the tangential portion of the fan blade would intersect if continued to the periphery of the 95 rotor.
12. A blast fan comprising a rotary member having a central intake and fans having flat portions entering the intake opening to an extent less than half the diameter of said 100 intake opening and provided with substantially radial flat continuations connected to the tangential portions of the fan blades and terminating at the outer edge of the rotary member of the fan, the said tangential portions being at an angle of about 20° to the radius of the fan rotor which the tangential portions if continued would intersect at the 105 periphery of said rotor.
13. A blast fan having cheek plates and 110 main and intermediate blades having flat substantially radial portions extending inwardly from the periphery of the cheek plates and flat tangential portions terminating respectively inside and outside of the 115 limits of the fan orifice, the intermediate blades terminating at the inner edge of the cheek plates and the main fan blades terminating beyond the inner edge of the same and extending into the fan orifice, the said 120 tangential portions being each at an angle of about 20° to the radius of the fan rotor which the tangential portions would intersect if continued to the periphery of the fan rotor.
14. A blast fan comprising a rotary member having a central substantially open intake throat, main blades tangentially disposed for a greater portion of their length 125 and having their tangential portions enter- 130

ing said throat for a distance and disposed at an angle of about 20° to the radii of the fan rotor which the tangential portions would intersect if continued to the periphery 5 of the said rotor, the said main blades terminating at their outer ends in substantially radial sections, and shorter blades between the main blades and also composed of tangential inner and substantially radial outer 10 portions, the outer ends of all the blades terminating at the same distance from the axis of the rotor.

15. A blast fan provided with a rotor having a substantially unobstructed central intake throat section and provided with cheek plates beyond the throat section, and fan blades mounted between the cheek plates and comprising a series of equally spaced blades having their inner ends flat and at an angle 20 of about 20° each to a radius of the fan rotor which the inner end of the blade if extended would intersect at the periphery of the said rotor, the inner end of each fan blade entering the throat section for a distance less than half the diameter thereof, 25 and other supplemental blades between the main blades and having flat tangential portions terminating at their inner ends at a point exterior to the throat section, the degree 30 of tangency of the supplemental blades being similar to that of the main blades, and all the blades having their outer ends flat and substantially radial and terminating at the outer periphery of the rotor.

35 16. A blast fan rotor having a number of

equally spaced main blades and an equal number of intermediate blades, with the sum of the areas of all the spaces between the inner ends of each main blade and the active face of the preceding blade in a plane perpendicular thereto, approximately equal to the area of the intake orifice of the fan. 40

17. A blast fan rotor having a number of main blades and other shorter blades all terminating at the periphery of the rotor, 45 the total number of blades bearing such a relation, substantially as described, to the diameter of the rotor that the peripheral distance between the outer ends of the fan blades is approximately constant for all 50 commercial sizes of blast fans.

18. A blast fan having a casing with a central intake opening and a rotor having a central opening of greater diameter than the intake opening in the casing, said rotor 55 having blades extending into said intake opening in the casing and being separated from the walls of the casing by a clearance space communicating with the active portion of the rotor through the central opening 60 thereof exterior to the outer limit of the intake opening of the casing.

In testimony that I claim the foregoing as my own, I have hereto affixed my signature in the presence of two witnesses.

DANIEL F. LEPLEY.
